CONTINUOUS DYEING AND DEVELOPING MACHINE

Bernard V. Stec, East Paterson, N. J., assignor to Botany Worsted Mills, Passaic, N. J., a corporation of New Jersey

Application October 27, 1944, Serial No. 560,646

6 Claims. (Cl. 68—9)

1

The present invention relates to machines for dyeing lengths of continuously moving fabric webs, and in such manner that the web is passed through primary and secondary dye baths with intermediate roll pressure means and thence into a development chamber within which heat is provided, as by steam coils. In this chamber the fabric web is led over the lowermost of a series of separator rolls and thence passes over one or plurality of rolls carrying longitudinally extended slats, the web then being led to the upper area of a chain-feed, consisting of two or more spaced chains carrying between them spaced slats or bars upon which the web rests in its movement from one end of the chain to the opposite end. After leaving the chain-feed the web is carried downward and led over the second one of the separator rollers and thence up, as before, to and over the chain-feed and thence down to the third one of the spacing rollers, the web moving in the same way to each one of the spacing rollers until the layers of the fabric web on the chain are equal to the number of spacing rollers employed, and the initial end of the web lies at the inside or lower face of the pile at the discharge end of the feed-chain. At this point the web is led over a turning bar and out of the casing in which the aforesaid elements are contained. By means of such instrumentalities, in the combination, the fabric web is dyed with uniformity throughout, and the dye development may be adjusted as to time without affecting the speed of the machine, by simply changing the number of the separator rollers and hence the number of laps built up upon the feed-chain prior to the turning and discharge movement of the fabric web from the machine.

The invention will be described in detail, with reference to the accompanying drawings, in which:

Figure 1 is a view in sectional elevation showing an embodiment of the machine.

Figure 2 is a view in elevation, partly broken away, showing the drive face of the development chamber.

Figure 3 is a plan view, partly in sections, showing the turning bar and the turning and discharge roller and certain driving connections.

Figure 4 is a fragmentary and schematic view, in perspective, showing the action of the turning bar.

Figure 5 is perspective view of one of the slat-carrying feed rolls.

Figure 6 is a fragmentary end view of the structure shown in Figure 5 with 5 laps of the fabric web supported by the slats.

Figure 7 is a horizontal section through the secondary dye chamber showing the mounting of the dancer roll therein.

Figure 8 is a vertical section through one of

2

the chains of the chain-feed showing a plurality of laps of fabric web on two bars of the chain.

Referring to the drawings, I have shown schematically in Figure 1 a base member 1 which carries a frame 2. The frame will consist of spaced sides supporting between them a primary dye chamber indicated at 3, and at the lower area of the chamber will be disposed a guide roller 4 for the fabric web 5 extending downwardly from a guide roller 6. Between the vertical frame members is a second guide roller 7, over which the wet web of fabric is led in its passage between squeeze rollers 8, 8x, the latter acting to press the dye into the fibers of the web and also to remove excess dye. One of the rollers may be pressed toward the other by the fluid pressure means indicated at 9 and which customarily will consist of a cylinder with a piston therein the piston being enacted to a rod 10 engaging one or both of the shaft supporting arms 11 for the roller 8.

After leaving the squeeze rolls the fabric web passes over guiding roll 12 and downwardly under a dancer roll 13 within secondary dye tank 14 and thence upwardly into the dye developing chamber. Within chamber 14 and at each side thereof, may be disposed vertical guide channels 15 for the outwardly projected shaft ends of the dancer roll.

The development chamber may be of any desired form and construction and is closed except for inlet and outlet passage ways for the travelling web. In Figure 1 the casing of the chamber is shown in vertical section as constructed of detachable elements and the chamber is generally indicated at 16. Inasmuch as the chamber except for one or more face plates may be of unitary construction the section lines through the detachable units thereof are, for convenience of illustration, extended in the same direction.

The entrance aperture for the development chamber casing is indicated at 17 and above it is a guide roll 18 over which the web is led to the spaced slats of a feed roll 19. This roll may be of any suitable construction, including that illustrated in Figure 5. The construction in that figure consists of a shaft 19x carrying spaced disks 19, which in turn carry spaced slats 19xx. In the drawing, Figure 1, four of the said feed rolls 19 are employed and each may have the same construction.

As the fabric web completes a downward movement from the initial feed roll 19, the latter being positively driven it passes over the lowermost end initial separator roll 20, from which the web passes to the second feed roll 19, and thence to a third feed roll 19, from which the web is led to the bars of the chain drive.

The chain drive may consist of two chains or the equivalent flexible lengths (one of the chains

being shown in Fig. 1, at 21). Transversely extending bars 22 are carried by the chains, and the chains and bars, with their driving elements constitute the chain drive. These driving elements are the shafts 23 and two sprockets on each shaft, one for each chain 21, one set of sprockets being indicated at 24, Fig. 1. The shafts for the lower rolls 19 are shown at 19x.

The shafts 23 for the chain drive, and also the shafts 19x may be journaled in bearing members (not shown) carried by the face walls 16x and 16xx of the casing 16 for the developing chamber, and these shafts may carry sprocket wheels 25 engaged by drive chain 26 which may run over either sprocket wheels 27 (Fig. 2). One of the said shafts may be positively driven, by any suitable means for effecting rotation of the shafts 19x and 23 to effect the drive.

In Fig. 1 I have shown means for heating the interior of the developing chamber i. e. the steam manifolds 21 and steam pipes 28.

The web of fabric after being led under each of the separator rolls 20 to thereby build up laps of fabric upon the chain drive equivalent to the number of separator rolls 20, shown in the drawing, passes to suitable guide rollers 29 (Fig. 3) and under a smoothing plate 30, if desired. And the endless belt 31 may serve as a support for the web as it advances toward the turning bar 31 (Fig. 3). This belt may be led over the pulleylike members 32 of two drive shafts 33 carrying driving pulleys connected by belt 34 and short belt 35 with a primary drive shaft 36. Additional shafts 33 with belts supporting wheels (not shown) may be provided. It will be understood that the means for feeding the web to the turning bar, and for carrying the web from the turning bar to a point exterior to the developing chamber may be widely varied from the means illustrated in Figure 3, the latter figure being largely schematic and suggestive of suitable instrumentalities. Thus synchronized motors 37 may be employed for the entire drive system. These motors carrying pulleys 38 connected by belts or chains 39 with pulleys on the rearward 1 of the shaft 33 which shaft may project laterally of one of the frame members 40 for the carrying of a pulley 41 which receives chain 34 and the carrying of a second pulley receiving chain 35 led to shaft 36. Shaft 36 may be connected by bevel gears 42 with the shaft 43 from which power is taken for the operation of the chain feed and feeds for the shafts 19x.

From the development chamber the web will pass through an opening indicated at 44 (Fig. 1) and onto a series of delivery rollers 45. The formation of the base area of the developing chamber, it being V-shaped enables economy in the quantity of treating solution employed in the chamber, and it will be seen that the fabric web passes through the treating solution as a layer entirely independent of other layers as to contact therewith, the number of immersions of each portion of the web being equivalent to the number of separator rolls employed.

It will be understood that the time of travel of the fabric web through the development chamber while controlled by the number of separator members 20, may also be regulated by the driving speed of the machine and usual controls will be applied for that purpose. It will also be understood that the chain-feed at the upper area of the development chamber may be independently driven as by means of a sprocket and chain

arrangement which does not include the slatted rolls on shafts 19x. In fact these slatted rolls may be idlers if desired.

I have shown in the drawings a usual type of turning bar with a rounded edge for immediate contact with the fabric web. Any suitable form of turning instrumentality may be employed as for example a round rod or roll. When the slatted rolls 19 are positively driven the drive will, of course, be synchronized with the chain-feed. Also, it will be understood that the belt 31 at the fabric web turning device may be eliminated if desired, inasmuch as there will be sufficient tension upon the fabric web as it is drawn out of the development chamber to coact with the turning bar 31 for maintaining the fabric web in straight lines.

Having described my invention, what I claim and desire to secure by Letters Patent, is as follows:

1. A continuous dyeing machine for fabrics and the like comprising a development chamber, means for guiding a web of fabric through at least one dye bath and into said chamber, an endless conveyor within the chamber at its upper area and adapted to give underlying support substantially throughout lengths of fabric led thereby from one side to the opposite side of the chamber, said endless conveyor consisting of parallel chains and spacing members connecting the same, a plurality of rotary supports for said parallel chains, a plurality of superposed fabric-web separator rolls below said endless conveyor, means for guiding the web of fabric over one of such separator rolls thence over the endless conveyor and thence successively over the remaining separator rolls and the conveyor, means for imparting operative movement to the conveyor, and fabric-web discharging means above the separator rolls for effecting the passage of the web out of the development chamber.

2. A continuous dyeing machine for fabrics and the like comprising a development chamber, and in combination with means for applying dye material to a web of fabric, an endless conveyor within the chamber at its upper area and adapted to give underlying support substantially throughout lengths of fabric led thereby from one side to the opposite side of the chamber, said endless conveyor consisting of parallel chains and spacing members connecting the same, a plurality of rotary supports for said parallel chains, a plurality of superposed fabric-web separator members spaced from said endless conveyor, means for guiding a web of fabric into said development chamber and over each of said separator members in succession and over said endless conveyor prior to the passage of the web over each of the separator members following the initial one, means for imparting operative movement to the conveyor, and fabric-web discharging means for effecting the passage of the web out of the development chamber.

3. A continuous dyeing machine for fabrics and the like comprising a development chamber having a solution-carrying base area progressively decreasing in transverse area and volume capacity from top to bottom thereof; an endless conveyor within the chamber at the top area thereof and adapted to give underlying support substantially throughout lengths of fabric led thereby from one side to the opposite side of the chamber, said endless conveyor consisting of parallel chains and spacing members

connecting the same, a plurality of rotary supports for said parallel chains, a plurality of elongated separator members arranged in a vertical row below said endless conveyor, a plurality of rotary fabric-web supporting and driving members intermediate the endless conveyor and the separator members, and driving means for said endless conveyor.

4. A continuous dyeing machine for fabrics and the like comprising a development chamber, and in combination with means for applying dye material to a web of fabric, an endless conveyor within the chamber disposed at an upper area thereof and adapted to give underlying support substantially throughout lengths of fabric led thereby from one side to the opposite side of the chamber, said endless conveyor consisting of parallel chains and spacing members connecting the same, a plurality of rotary supports for said parallel chains, the chamber having a solution-holding area at the base thereof, and the endless conveyor comprising spaced endless flexible members and transversely extending spaced connecting bars for said members, which bars are adapted as carrier-supports for a web of fabric, a plurality of spaced separator members within said solution holding area and adapted to separate sectional areas of a continuous web of fabric led over said endless conveyor, and means for withdrawing an end of said fabric web from a pile of layers of said web of fabric on said endless conveyor, and at the bottom of the pile, and for passing said end of the web out of the development chamber in a direction transversely to the movement of the web in its passage from the endless conveyor.

5. A continuous dyeing machine for fabric and the like constructed in accordance with claim 4, in which said withdrawing means is dis-

posed at a place intermediate the endless conveyor and the separator members, and formed as an inclined turning bar.

5 6. A continuous dyeing machine for fabrics and the like comprising a development chamber, an endless conveyor within the chamber at the top area thereof and adapted to give underlying support substantially throughout lengths of fabric led thereby from one side to the opposite side of the chamber, said endless conveyor consisting of parallel chains and spacing members connecting the same, a plurality of rotary supports for said parallel chains, a plurality of elongated separator members arranged in a vertical row below said endless conveyor, a plurality of rotary fabric-web supporting and driving members intermediate the endless conveyor and the separator members and disposed so that alternate faces of the fabric are brought into contact with successive separator and intermediate rotary members.
